Y SOL, OF TRINIDAD, SANTA CLARA, CUBA.

NON-REFILLABLE BOTTLE.

1,254,896.

Specification of Letters Patent. Patented Jan. 29, 1918.

Application filed October 5, 1916. Serial No. 123,935.

To all whom it may concern:

Be it known that I, JOSE VILA FERNANDEZ, a subject of the King of Spain, residing at Campechuela, in the Province of Oriente, 5 Cuba, have invented certain new and useful Improvements in Non-Refillable Bottles; and I do declare the following to be a full, clear, and exact description of the invention, such as will enable others skilled 10 in the art to which it appertains to make and use the same.

This invention relates to improvements in non-refillable bottles, the primary object being to provide means which will positively 15 preclude reuse of the bottle in any manner.

The secondary object is to provide a device of this character which is equipped with pneumatically controlled means for preventing the refilling of the bottle by the 20 use of pneumatic apparatus.

Still another object is to provide a simply constructed bottle which will be very inexpensive to manufacture, yet which will be extremely efficient in operation.

25 With these and other objects in view, my invention resides in the novel features of construction, combination and arrangement of parts which will be hereinafter more particularly described and claimed 30 and shown in the drawings wherein:—

Figure 1 represents a central vertical section through a bottle constructed in accordance with the invention;

Fig. 2 is a similar view of the upper end 35 of the bottle showing the parts arranged as they will appear when the contents of the bottle is being emptied therefrom;

Figs. 3, 4 and 5 are horizontal sections 40 taken on the planes of the lines 3—3, 4—4, 4—5—5 of Fig. 1; and

Fig. 6 is a detail section showing how the parts will operate when it is attempted to extract the air from the empty bottle for the purpose of refilling it by pneumatic 45 apparatus.

Referring more particularly to the drawings, it will be seen that the bottle 1 in which the non-refillable means is disposed has an enlarged neck 2, the latter being connected 50 to the body 3 of the bottle by a neck of ordinary size as shown at 4. At the junction of the enlarged and reduced necks 2 and 4 is provided with a shoulder which forms a

valve seat 5 for coöperation with a valve which will later be described.

Within the enlarged portion 2 is disposed 55 a stopper 6 in which is housed the operating means for preventing the refilling of the bottle. This stopper 6 is substantially cylindrical and has its bottom end open, the upper end thereof being closed by a top 7, the latter portion having a plurality of recesses 8 on its periphery to allow liquid to flow from the body of the bottle. This liquid enters the cavity of the stopper and 65 flows therefrom through the outlets 9 in the vertical wall thereof and into the recesses or grooves 10 provided in the inner face of the neck 2, the upper ends of these grooves communicating with the recesses 8. It will 70 be noted that the top 7 of the stopper is disposed below the top of the neck 2 so that a cork C of any preferred construction may be inserted to close the bottle during storage or transportation.

75 The stopper 6 may be locked within the neck of the bottle by any preferred means as is usual in devices of this character. In the present instance, both the bottom portion of the vertical wall of the stopper and 80 the bottom portion of the neck 2 is annularly grooved as shown at 11 for the reception of a locking member 12. This member is in the form of a split collar which has its lower edge slashed and the 85 fingers thus formed bent upwardly into the position shown in Figs. 1 and 2. After the bottle has been filled with a suitable liquid and before the stopper 6 has been inserted in the neck thereof, this locking member 90 is disposed in the groove in the latter, the stopper then being forced into the neck 2 until its lower end engages the shoulder at the intersection of the necks 2 and 4, whereupon the fingers of the locking member 95 will spring into engagement with the groove in the bottom portion of the neck 2. This prevents the removal of the stopper.

Within the cavity of the stopper 6 is disposed a pneumatically controlled valve member 13, the latter comprising a valve 14 for coöperative engagement with the valve seat 5, and a valve stem 15. The stem is preferably formed integrally with 100 the valve 14 and is composed of two crossed

blades 16 which have their inner ends cupped as shown at 17 to receive an operating ball 18. This ball normally lies at the bottom of the bottle 1, but when the 5 same is inverted to empty the contents therefrom, the ball rolls into the seat formed at the cupped end 17. The upper end of the valve member has an air chamber 19 formed thereon, said chamber being in the 10 form of a cylindrical open ended tube. The air chamber is closed by a plunger 20 which has a fluid-tight connection therewith, yet is slidable to a certain extent therein.

The valve member 13 is guided both by 15 the stem 15 which is slidable in the reduced neck 4, and by the cylindrical air chamber 19, the latter being slidable in a guide sleeve 21 which depends from and is formed integrally with the inner face of the top 20 7 of the stopper. Also depending from the inner face of the top 7 and within the sleeve 21 is a boss 22 which has an expansion helical spring 23 attached thereto, the inner end of this spring engaging the closure 20, 25 which, owing to its fluid-tight connection with the air chamber, will act against the air contained therein tending to compress the air and thereby force the valve normally into closed position.

30 The movable parts of the device are protected from tampering both by the upright cylindrical portion of the stopper 6 and the metallic guard shell 24 which is substantially cylindrical and is disposed within 35 the cavity of the stopper. From Fig. 2 it will be seen that the liquid from the body of the bottle flows, when the latter is inverted and the valve 14 open, through the contracted neck 4 and into the interior of 40 the guard shell 24, from whence it flows by way of the notches 25 formed in its upper edge into the space between the outer wall of said guard shell and the inner wall of the stopper. From this space, it flows 45 through the outlet ports 9, the grooves 10 and out through the recesses 8 in the top 7 to the receptacle.

As hereinbefore mentioned, whenever the bottle is inverted, the ball 18 rolls into 50 the seat 17 formed in the end of the valve stem, and thus overcoming the tension of the spring 23 causes the valve 14 to move away from its seat 5 thereby allowing the liquid to flow from the bottle. Should it 55 be attempted to refill the bottle when the same is in its upright position, the liquid will be prevented from entering the body of the latter because the spring 23 bearing against the plunger of the air chamber causes the valve 14 to tightly engage the seat, the ball 18 being now at the bottom 60 of the bottle where it is inoperative. It is equally obvious that it will be impossible to refill the bottle under ordinary conditions when the same is inverted.

Should it be attempted to refill the bottle by pumping out all of the air therein in order to create a vacuum, the air chamber in the valve member comes into operation. Under normal conditions, this part is largely 70 inoperative because the air contained therein is under the same pressure as the outside air, thus the closure 20 will remain immovable. When, however, the air is sucked from the bottle, the air within the chamber 75 19 tends to expand, and expanding in all directions equally will tend to force the closure outwardly as shown in Fig. 6. This equal expansion of the air within the chamber also exerts its force to raise the valve 80 14 into engagement with its seat, thereby preventing the entrance of any liquid. When the suction has been removed, the closure and the other parts will return to their normal positions. From the foregoing description, it is obvious that I have produced a bottle which it will be impossible to refill under all conditions.

Having thus described my invention, what I claim is:—

1. The combination with a bottle; of a stopper disposed in the neck thereof and a pneumatically controlled valve in said stopper to prevent unauthorized refilling of the 90 bottle.

2. The combination with a bottle; of a stopper disposed in the neck thereof, a valve member movable in said stopper, and having a fluid chamber therein, a pneumatically controlled plunger slidable in said chamber, 100 and means between said plunger and stopper to hold said valve normally closed.

3. The combination with a bottle; of a hollow stopper disposed in the neck thereof, a valve member movable in said stopper, a cylindrical fluid chamber carried by said member, one of the ends of said chamber being open, a sleeve extending from said stopper within the cavity and slidably engaging said chamber, a boss also extending 105 from said stopper within said sleeve, a closure slidable in the open end of said chamber and having a fluid-tight engagement with the walls thereof, and an expansion spring secured to said boss and engaging 110 said closure.

4. The combination with a bottle, of a cylindrical tubular stopper disposed in the neck thereof, said stopper being open at its inner and closed at its outer end, said stopper and the inner wall of the neck of said bottle having passageways, a sleeve extending inwardly from the closed end of said stopper, the sides of the sleeve being parallel to the wall of said stopper, a substantially cylindrical guard disposed between the wall of the stopper and said sleeve, a valve member movable in said stopper, an open-ended fluid chamber on said member and slidable in said sleeve, a fluid-tight clo- 120 125 130

sure in the open end of said chamber, and an expansion spring in said sleeve, said spring engaging said closure and the closed end of said stopper to hold said valve normally closed.

5. The combination with a bottle; of a stopper disposed in the neck thereof, a valve movable in said stopper, an air chamber in said valve, and a pneumatically operated member in said chamber to hold said valve closed under expansion of the air in said chamber.

10. The combination with a bottle, of a stationary stopper disposed in the neck thereof, a valve member movable in said

stopper, a valve formed on said member, said member having an air chamber therein, a pneumatically controlled plunger slidable in one end of said chamber and in fluid tight engagement with the walls thereof, and a 20 spring between said stopper and closure to compress the fluid in said chamber and hold said valve closed.

In testimony whereof I have hereunto set my hand in the presence of two sub- 25 scribing witnesses.

JOSE VILA FERNANDEZ.
